UNITED STATES PATENT OFFICE.

JOHN W. VANCE, OF SAGINAW, NORTH CAROLINA.

SADDLETREE.

949,101.

Specification of Letters Patent. Patented Feb. 15, 1910.

Application filed July 2, 1909. Serial No. 505,766.

To all whom it may concern:

Be it known that I, JOHN W. VANCE, a citizen of the United States, residing at Saginaw, in the county of Mitchell and 5 State of North Carolina, have invented certain new and useful Improvements in Saddle-trees, of which the following is a specification.

This invention comprehends certain new 10 and useful improvements in saddles, and the invention has for its object an improved saddle tree which embodies a novel arrangement of parts through the instrumentality of which it is rendered susceptible of being 15 quickly and conveniently adjusted in contour, so as to fit snugly the back of the horse to which it is applied. The saddle is thus retained against any slipping movement, whereby to preclude chafing the 20 horse's back and to insure ease and comfort to both the rider and the horse.

With this and other objects in view that 25 will more fully appear as the description proceeds, the invention consists in certain constructions and arrangements of the parts that I shall hereafter fully describe and then point out the novel features of in the appended claims.

For a full understanding of the invention 30 and the merits thereof and also to acquire a knowledge of the details of construction, reference is to be had to the following description and accompanying drawing, in which:

35 Figure 1 is a side elevation of a saddle constructed in accordance with my invention; Fig. 2 is a transverse section of the saddle tree; and, Fig. 3 is a perspective view thereof.

40 Corresponding and like parts are referred to in the following description and indicated in all the views of the drawing by the same reference characters.

45 My improved saddle tree embodies two longitudinal saddle bars 1 that are arranged to extend on opposite flanks of the horse in the customary manner and are connected at their front and rear ends respectively by a pommel 2 and a cantle 3. The pommel 50 and cantle are substantial duplicates in structure and each is composed of inner and outer arch-shaped springs or bows 4 and 5 which are secured terminally to the corresponding ends of the saddle bars. The

inner spring is disposed directly beneath 55 the outer spring and is relatively shorter and somewhat weaker than the same. The saddle bars 1 are interposed between the adjacent ends of the springs, as best seen in Fig. 2, so as to space them apart. At 60 their middle points the springs are normally maintained in spaced relation through the medium of an interposed helical expansion spring 6 that encircles a bolt 7. The bolt is passed upwardly through the inner and 65 outer springs and has its threaded extremity upstanding from the latter and adapted for the reception of a nut 8. When this nut is tightened the bolt 7 is moved upwardly 70 against the compression of the spring 6 and the middle portion of the relatively weak spring 4 is drawn toward the outer spring 5, whereby to move the straddle bars 1 toward each other and increase the curvature of the saddle tree, as illustrated by dotted lines 75 in Fig. 2.

9 designates a flat metallic brace bar which is attached at an intermediate point by the bolt 7 to the middle of the inner spring 4, the ends of the bar extending oppositely between the spaced springs 4 and 5 and being normally spaced apart from the outer spring (see Fig. 2). However, when the inner 80 spring is drawn upwardly toward the outer spring, the brace bar 9 bears terminally 85 against the inner surface of the latter, to strengthen the structure as a whole.

The saddle tree may be padded and covered in any approved manner, as this in 90 itself forms no part of the present invention and is left to the discretion of the saddle maker. It is to be borne in mind however, that the nuts 8 of both the pommel and cantle are arranged on the outside of the 95 covering so as to be readily accessible for use in adjusting the saddle.

From the foregoing description in connection with the accompanying drawing, it will be apparent that I have provided an improved saddle tree which admits of the 100 saddle being positively and conveniently adjusted in contour to fit horses of different sizes or to meet any particular requirement of the rider; which may be advantageously employed in connection with both ladies' 105 and gentlemen's saddles; which embodies to a marked degree the characteristics of simplicity, durability and strength and is

otherwise particularly attractive; and which consists of comparatively few parts that are not likely to get out of order.

A U-shaped metallic loop 10 preferably straddles the nut 8 at the front of the saddle and is pivoted terminally thereto. This loop has been found convenient for manually operating the nut; for attaching the reins; and for various other purposes that will at once present themselves to the user of the saddle.

Having thus described the invention what is claimed as new is:

1. As a new article of manufacture, a saddle tree embodying longitudinal saddle bars, pairs of inner and outer arch-shaped springs connecting the saddle bars and secured terminally thereto, the springs of each pair being spaced apart and the inner spring being weaker than the outer, and means for drawing the middle portions of the respective inner springs toward the outer springs to change the contour of the saddle.
2. As a new article of manufacture, a saddle tree embodying longitudinal saddle bars, a pommel and a cantle, the pommel and cantle each comprising a pair of inner

and outer arch-shaped springs secured terminally to the saddle bars and spaced apart between the same, a bolt passed through the middle portions of the springs, an expansion spring encircling the bolt and interposed between the springs, and a nut working on the extremity of the bolt for drawing the inner and outer springs together against the force of the expansion spring.

3. As a new article of manufacture, a saddle tree embodying longitudinal saddle bars, pairs of inner and outer arch-shaped springs connecting the saddle bars and secured terminally thereto and spaced apart between the same, means for drawing together the middle portions of the respective pairs of springs, and brace bars secured at intermediate points to the middle portions of the inner springs and arranged between the springs of each pair and adapted to bear terminally against the outer springs.

In testimony whereof I affix my signature in presence of two witnesses.

JOHN W. VANCE. [L.S.]
